BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,293,235.

Specification of Letters Patent.

Patented Feb. 4, 1919.

Application filed August 10, 1915. Serial No. 44,680.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates principally to the type-actions of typewriting machines, and one of its main objects is to produce a simple, inexpensive and compact mechanism suitable for a portable typewriting machine.

The type-bars are relatively short, and pivoted in a short arc close to the platen, preferably striking upon the top side of the platen, and normally extending forwardly to a position close to the keyboard and about on a level therewith; thus producing a machine that is of but very little height, and also short from front to back.

The room at the pivots of the type-bars in such a machine is necessarily reduced, and the room for the mountings and operating means is limited. Moreover the keyboard is wider than the system of type-bars, and very much wider than the length of the pivot-arc of the type-bars, since the latter converge from the types rearwardly to their pivots.

In order to meet all these conditions, I extend the key-levers convergently from the keyboard, and pivot them under the type-bars, the system of type-bars and key-levers forming a bank behind which runs the platen, which may be about on a level with the type-bars. The rear portions of the levers are arranged in the same converging planes in which the type-bars swing, and the levers are always beneath the type-bars, so that no more lateral room is taken up by the levers than would be needed in any case for the type-bars themselves.

Each type-bar with its lever is pivoted compactly upon an erect thin plate, which constitutes a bracket or hanger; and also pivoted upon said plate is a sub-lever in the form of a bell-crank, which, for lateral compactness, may be connected to the key-lever by a knuckle-joint. These bell-cranks extend upwardly from the key-levers and engage in slots in the type-bars; the plates

which form the hangers having a converging arrangement corresponding to the radial positions of the type-bars. Each plate may be forked to seat in grooves cut in the front and rear sides of the segment; suitable means being provided for locking the hangers to the segment. Each plate, with its attached type-bar, key-lever and sub-lever, may be detached or attached as a unit. Moreover, the segment, with the attached hangers, key-levers, type-bars, and sub-levers, may be removed bodily or as a unit from the machine, for purposes of repair or examination, and to admit of substitution of another system of type-bars, with different types, and with similar or different keys, as may be required.

The space-key at the front of the keyboard is mounted to be capable of displacement rearwardly over and back of the keys, to be out of the way when the machine is to be packed up for transportation, thus reducing the bulk.

Other objects and advantages will hereinafter appear.

In the accompanying drawings, Figure 1 is a diagrammatic side elevation showing a type-action in printing position.

Fig. 2 is a perspective view of a type-bar hanger.

Fig. 3 is a sectional side elevation taken about centrally of the machine from front to rear, and showing the type-actions and appurtenances.

Fig. 4 is a plan of the machine. Fig. 5 is a sectional front elevation of type-bar, sub-lever, hanger and key-lever, showing these four parts so closely arranged that they occupy the widthwise space of only two parts.

Upon the top of a shiftable platen 1, at a point just forward of a line passing vertically through the platen axis, strike types 2, mounted on type-bars 3, pivoted at their rear ends at 4 to swing preferably through nearly half a circle; the types normally lying at about the same height as the keys 5, and nearly on a level with the top of the platen 1, so that a machine of but little height is produced, and so that the writing will be clearly visible to the operator looking down upon the machine. The keys 5 are mounted

upon the forward ends of levers 6 of the second order, which extend rearwardly and terminate forwardly of the platen, being fulcrumed upon studs 7; the platen 1 being in 5 a depressed or sunken position behind the bank formed by the assemblage of key levers and type-bars.

The key levers are connected to the type-bars by means of sub-levers, the latter pivoted upon studs 8 and comprising arms 9 10 extending upwardly and provided with driving wrists or pins 10 to engage slots 11 in the hub portions of the type-bars; said slots being of great length and curved suitably to accelerate the speed of the type-bars during their printing strokes.

In the neighborhood of the type-bar pivots, it will be observed that there is very little room, owing to the shortness of the 20 type-bars and to the undesirability of setting the types at excessive angles upon the bars, necessitating the assemblage of the bars in as small an arc as possible. The type-bars accordingly consist of thin blades 25 of sheet metal, mounted upon thin, plate-like hangers 12, which are erected closely side by side upon a segment 13; the key lever bearings 7 being also fixed upon said hangers, as well as the sub-lever bearings 8. The hangers, which are converging, may be formed of thin blades; and the type-bars may lie against the hangers. The key levers may also extend alongside of the hangers, each key lever directly under its 35 type-bar, so that no extra lateral room is demanded at this crowded portion of the machine for the accommodation of the key levers.

The sub-levers 9 may have short arms 14, 40 connected to the key levers by knuckle joints 15, so that the sub-levers may also lie against the hangers and just over the key levers, and beneath the type-bars, so that no lateral room is taken up by the sub-levers. Between 45 their ends the sub-levers may be bent or offset laterally at 16, to occupy the same planes as the hangers, that is, so that the upper portions of the sub-levers will be on the same sides of the type-bars as are the hangers 12. The hangers are provided with bends at 50 their upper ends 17, to carry the wrists 10, said bends enabling the sub-levers or bell-crank to clear the hangers 12 when in printing position, as at Fig. 1.

The sub-levers 9 cross the type-bars, that is, extend upwardly from beneath the type-bars to points of engagement at 10 with the type-bars, above the pivots of the latter; the length of each sub-lever from 8 to 10 being in excess of the distance between 8 and 4.

As will be seen at Fig. 4, the rear portions of the key levers directly underlie and extend along the converging type-bars. The key levers extend forwardly beyond the

type-bars, and have outwardly diverging 65 bends at 18, which terminate in parallel forwardly-extending key-bearing portions 19. The key levers work in converging planes, and, owing to the plan of the levers, as seen at Fig. 4, the point of application of 70 power upon each lever is in or very nearly in the plane in which said lever works, so that liability of binding or other faulty action of the lever is reduced or eliminated. In other words, the lever extends forwardly 75 from its pivot along a line which, if extended, would touch or nearly touch its own key; the crossing of the key levers, one by another, being avoided by having the key-bearing portions 19 extend substantially in 80 parallelism directly back from the keys, and this arrangement of the key-bearing portions being facilitated by the extra converging portions or bends 18 of the levers, between the key-bearing portions and the rear 85 portions that underlie the type-bars.

Each key lever may be bent upwardly at 20 near the segment 13, and downwardly at 21 to underlie the sub-lever 9. The key levers may equal or exceed the type-bars in 90 length, thus avoiding undue slanting of the keys when depressed, without extending back to a position to interfere with the platen or its appurtenances. *

It will be understood that the key lever 95 fulcrums 7 are arranged in an arc concentric to the arc of the type-bar pivots 4; and that the sub-lever bearings are also arranged in an arc concentric to said other arcs. The strokes of the sub-levers may be uniform; and the arm 14 may be made as short or as long as required in each case, so as to give the keys uniform strokes. A returning draw spring 22 may extend forwardly from each sub-lever arm 9 to a point of connection 23 to its key lever, so that each hanger, type-bar and lever may be handled as a unit.

Each hanger 12 is formed at its lower portion with forks 24, 25, to bestride the segment 13, which has on its forward and rear 110 sides downwardly-extending slots 26, to form seats in which the hanger may fit tightly. Each hanger may be locked in place by a locking tongue 27, sprung out from the side of a fork, and engaging under 115 a shoulder 28 formed in the notched portion of the segment. In other words, on the front side of the segment may be upper and lower ribs to form seats for the hangers, and the tongues 27 may catch under the upper 120 ribs. The tongue will spring out when the hanger is pressed down in position, and may be sprung back again by the point of a screw-driver or other tool, when it is desired to remove the hanger. The grooves in the 125 segment may be placed closely together, so that the hangers may be assembled with the necessary compactness; while the entire

hanger system forms a very firm, reliable, compact and inexpensive support for the type-bars, etc.

The segment may be secured by screws 5 upon a crossbar 30, and the latter may be secured by screws 31 to ears 32 extending inwardly from the sides 33 of the type-writer framework, so that said bar 30 may be detached from the machine, together 10 with the segment and the entire set of type-actions, bodily. To facilitate this removal, the guide-comb 34 of the key levers is mounted by means of arms 35 and screws 36 upon the forward edge of said bar 30, to 15 be removed or replaced therewith; and upon said guide-comb 34 may be also carried by means of arms 37 a pad or rest 38 for the type-bars, and said arms 37 may also carry a stop 39 for the key levers when in 20 normal positions. Thus, by simply loosening the screws 31, the entire system of type-actions may be readily removed from the machine.

The platen 1 may be mounted upon any 25 suitable carriage, as indicated diagrammatically at 40, and the same may have a letter-feeding rack 41, which may be controlled by escapement dogs 42, 43, mounted upon a rocker 44 and having a returning 30 spring 45, all of conventional construction. This dog-rocker may be connected to a universal bar 46 placed beneath the key levers to remain in the machine when the type-actions are lifted out; said universal 35 bar having a returning spring 47. The universal bar may be made of considerable extent from front to back, and may be operated by any of a series of projections 48 formed upon the under edges of the key 40 levers, said projections being placed at suitable points on the levers to insure that the universal bar 46 shall be given the same stroke by every key.

The universal bar may be carried upon 45 arms 49, pivoted at 50 upon the frame work of the machine; and one of said arms may bear down upon a pin 51 provided upon arm 52, to which is pivoted at 53 the forward end of the link 54, whose rear end is pivoted 50 to the dog-rocker 44; the spring 45 serving to return not only said rocker but also the link 54 and the arm 52.

The space-key 55, arranged in the usual 55 position in front of the keyboard and extending along the same, is mounted to be swung upwardly and rearwardly over the keyboard to a position behind the same, as will be seen at Fig. 3, to render the machine somewhat less bulky for transportation purposes. For this purpose, the key 55 is mounted upon arms 56, and forms with said arms a bail which surrounds the front portion of the machine frame, being loosely pivoted upon the ends of pintles 57. The

provision of the arms outside of the ma- 65 chine frame facilitates the swinging up of the key to the dotted-line position at Fig. 3, enabling the bail to clear the various parts in the swinging motion.

When down in working position, the 70 arms 56 bear upon pins 58, which project from pendent arms 59 arranged outside of the machine frame, and fixed upon the outer ends of said pintles 57, the inner ends of the latter being rigidly connected by a bail 60, 75 which at one end drives backwardly a horizontal rod 61, which carries at its rear a tappet 62, to strike the end of the arm 52 and drive back the link 54, to operate the carriage-feeding dog-rocker 44; a returning 80 spring 63 being provided for the rod 61.

Variations may be resorted to within the scope of the invention, and portions of the improvements may be used without others.

Having thus described my invention, I 85 claim:

1. The combination of a system of key-levers extending rearwardly from the keyboard and converging at their rear ends, a system of converging brackets whereon said 90 key-levers are mounted, type-bars mounted on said brackets to strike at a common printing point, and sub-levers also mounted on said brackets to connect the key-levers to the type-bars. 95

2. The combination of a system of key-levers extending rearwardly from the keyboard and converging at their rear ends, a system of converging brackets whereon said key-levers are mounted, type-bars mounted 100 on said brackets to strike at a common printing point, sub-levers also mounted on said brackets to connect the key-levers to the type-bars, and a segment whereon said brackets are mounted for individual detachment. 105

3. The combination of a system of key-levers extending side by side rearwardly from the keyboard and converging at their rear ends, a system of converging brackets 110 whereon said key-levers are mounted, one bracket for each key-lever, type-bars also mounted on said brackets to strike at a common printing point, each type-bar operable independently of all the others, and a segment whereon said brackets are mounted for individual detachment. 115

4. The combination of a keyboard, a curving system of types of less width than the keyboard and in rear thereof, a system 120 of rearwardly converging bars whereon said types are mounted, a system of key-levers extending rearwardly from the keyboard and converging at their rear ends about coincidentally with the type-bars, and connections from the rear portions of the levers to the type-bars, said connections including sub-levers arranged about in the same con- 125

verging planes as the key-levers and type-bars.

5. The combination of a keyboard, a curving system of types of less width than the 5 keyboard and in rear thereof, a system of rearwardly converging bars whereon said types are mounted, a system of key-levers extending rearwardly from the keyboard and converging at their rear ends about 10 coincidently with the type-bars, connections from the rear portions of the levers to the type-bars, said connections including sub-levers arranged about the same converging planes as the key-levers and type-bars, and 15 a converging system of upright plates forming brackets on which the type-bars, key-levers and sub-levers are mounted.

6. The combination of a thin erect plate forming a hanger, a type-bar pivoted on one 20 side thereof, a key-lever pivoted to the same side of the hanger, and a sub-lever pivoted on the same side of the hanger as the key-lever and type-bar, and having a knuckle-joint connection to the key-lever and extending 25 to the type-bar.

7. The combination of a thin erect plate forming a hanger, a type-bar pivoted on one side thereof, a key-lever pivoted to the same side of the hanger, and a sub-lever 30 pivoted on the same side of the hanger as the key-lever and type-bar, and having a knuckle-joint connection to the key-lever and extending to the type-bar, and offset or bent between its ends, to bring it into the 35 same plane as the hanger.

8. The combination with a platen, of a system of thin erect plates forming hangers, a system of converging type-bars thereon, each type-bar pivoted to one side of its 40 hanger, a system of converging key-levers also mounted on said hangers, each key-lever pivoted on the same side of the hanger as its type-bar, and means to connect the key-levers and type-bars.

45 9. The combination with a platen, of a system of thin erect plates forming hangers, a system of converging type-bars thereon, each type-bar pivoted to one side of its hanger, a system of converging key-levers also 50 mounted on said hangers, each key-lever pivoted on the same side of the hanger as its type-bar, and means to connect the key-levers and type-bars, said connecting means including sub-levers also pivoted to said 55 hanger and extending from said key-levers to said type-bars.

10. The combination with a platen, of a system of thin erect plates forming hangers, a system of converging type-bars thereon, each type-bar pivoted to one side of its 60 hanger, a system of converging key-levers also mounted on said hangers, each key-lever pivoted on the same side of the hanger as its type-bar, and means to connect the 65

key-levers and type-bars, said connecting 65 means including sub-levers also pivoted to said hanger and extending from said key-levers to said type-bars, each sub-lever pivoted to its hanger on the same side thereof as the key-lever and type-bar. 70

11. The combination with a platen, of a system of thin erect plates forming hangers, a system of converging type-bars thereon, each type-bar pivoted to one side of its hanger, a system of converging key-levers 75 also mounted on said hangers, each key-lever pivoted on the same side of the hanger as its type-bar, and means to connect the key-levers and type-bars, said connecting means including sub-levers also pivoted to said 80 hanger and extending from said key-levers to said type-bars, each sub-lever pivoted to its hanger on the same side thereof as the key-lever and type-bar, and having a knuckle-joint connection with the key-lever, 85 and offset between its ends, its type-bar operating end being on the same side of the type-bar as the hanger.

12. The combination with a platen, of a system of thin erect plates forming hangers, 90 a system of converging type-bars thereon, each type-bar pivoted to one side of its hanger, a system of converging key-levers also mounted on said hangers, each key-lever pivoted on the same side of the hanger as 95 its type-bar, and means to connect the key-levers and type-bars, all of said plates, type-bars and levers mounted in front of the platen.

13. The combination with a platen, of a 100 system of thin erect plates forming hangers, a system of converging type-bars thereon, each type-bar pivoted to one side of its hanger, a system of converging key-levers also mounted on said hangers, each key-lever 105 pivoted on the same side of the hanger as its type-bar, and means to connect the key-levers and type-bars, all of said plates, type-bars and levers mounted in front of the platen, and the platen occupying a sunken position behind said plates.

14. The combination with a platen, of a system of thin erect plates forming hangers, a system of converging type-bars thereon, each type-bar pivoted to one side of its 115 hanger, a system of converging key-levers also mounted on said hangers, each key-lever pivoted on the same side of the hanger as its type-bar, and means to connect the key-levers and type-bars, all of said plates, type-bars and levers mounted in front of the platen, and the platen occupying a sunken position behind said plates, and the 120 type-bars mounted to strike upon the upper side of the platen and normally to extend 125 forwardly from said plates with their forward ends at about the height of the keyboard.

15. The combination with a system of key-levers converging at their rear portions and pivoted at their rear ends, of a system of recumbent converging pivoted type-bars, and a system of bell-cranks arranged forward of the type-bar and key-lever pivots and operating in substantially the converging planes of their connected type-bars, and each of a greater length than the distance between the pivots of the type-bar and bell-crank, and having a rearwardly-extending arm operated by the key-lever. 15
16. The combination with a system of key-levers converging at their rear portions and pivoted at their rear ends, of a system of converging pivoted type-bars, and a system of bell-cranks arranged forward of the type-bar and key-lever pivots and operating in converging planes, and each of a greater length than the distance between the pivots of the type-bar and bell-crank, and having a rearwardly-extending arm operated by the key-lever, each type-bar having a movement-accelerating slot, and each bell-crank having a pin to engage said slot. 20
17. The combination with a pivoted type-bar having a slot extending upwardly from its pivot, of a sub-lever pivoted below the type-bar and crossing the latter and having a pin to engage said slot at a point a substantial distance above the line joining the type-bar pivot and the type, and a key-lever connected to said sub-lever, said slot having a speed-accelerating form, whereby the speed of the type-bar is increased during the printing stroke. 30
18. The combination with a platen, of a system of thin erect plates forming hangers, a system of converging type-bars thereon, each type-bar pivoted to one side of its hanger, a system of converging key-levers also mounted on said hangers, each key-lever pivoted on the same side of the hanger as its type-bar, and means to connect the key-levers and type-bars, said connecting means including sub-levers also pivoted to said hanger and extending from said key-levers to said type-bars, each sub-lever pivoted to its hanger on the same side thereof as the key-lever and type-bar, each key-lever pivoted in rear of the sub-lever and bent to pass beneath the same, and having a knuckle-joint connection with the sub-lever in rear of the pivot of the latter. 40
19. The combination with a segment having radial slots on its front and rear sides, of type-bar hangers in the form of plates forked to bestride the segment and fit in the slots thereof, and means to fasten each hanger in position, said means comprising a spring-tongue formed in each hanger and sprung therefrom, and said segment having shoulders for locking engagement with said tongues. 50
20. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly extending arm operated by the key-lever, converging hangers on which are mounted said key-levers, type-bars and bell-cranks, and a segment on which said hangers are mounted; said key levers pivoted in rear of said segment and extending forwardly over the same. 55
21. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter. 60
22. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 100
23. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 105
24. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 110
25. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 115
26. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 120
27. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-bars and bell-cranks, and a segment on which said hangers are mounted; said key-levers pivoted in rear of said segment and extending forwardly over the same and bent down to pass beneath the bell-cranks, and having a knuckle-joint connection with the latter, said segment having downwardly extending slots on its front and rear sides, and said hangers forked to bestride the segment and seat in the slots thereof. 125

- of the type-bar and bell-crank and having a rearwardly-extending arm operated by the key-lever, converging hangers on which are mounted said key-levers, type-bars and bell-
5 cranks, and a segment on which said hangers are mounted; said key-levers pivoted in rear of said segment and extending forwardly over the same and bent down to pass beneath the bell-cranks and having a knuckle-
10 joint connection with the latter, said segment having downwardly extending slots on its front and rear sides, and said hangers forked to bestride the segment and seat in the slots thereof, each hanger, together
15 with its key-lever, bell-crank and type-bar, being removable as a unit from said segment.
24. The combination with a system of key-levers converging at their rear portions and pivoted at their rear ends, of a system of converging pivoted type-bars, a system of bell-cranks arranged forward of the type-bar and key-lever pivots and operating in converging planes, and each of a greater length than the distance between the pivots of the type-bar and bell-crank, and having a rearwardly-extending arm operated by the key-lever, converging hangers on which are mounted said key-levers, type-
25 bars and bell-cranks, and a segment on which said hangers are mounted; said key-levers pivoted in rear of said segment and extending forwardly over the same and bent down to pass beneath the bell-cranks, and
30 having a knuckle-joint connection with the latter; said segment having downwardly-extending slots on its front and rear sides, and said hangers forked to bestride the segment and seat in the slots thereof, each
35 hanger, together with its key-lever, bell-crank and type-bar, being removable as a unit from said segment, said unit including a returning spring for the type-bar, bell-crank and key-lever.
- 40 25. A hanger in the form of a plate, having a type-bar pivot, a key-lever pivot, a sub-lever pivot, and a forked portion for seating on a slotted segment, and also having a locking portion for locking the hanger on the segment.
- 45 26. The combination with a framework, of a segment mounted thereon, a system of type-bars mounted on said segment, a converging system of key-levers also mounted on said segment, a guide-comb for the key-levers connected to said segment, and connecting means between said key-levers and said type-bars; said segment, with the attached type-bars, connected key-levers and
50 guide-comb, being bodily dismountable from said framework.
- 55 27. The combination with a framework, of a segment mounted thereon, hangers slidably mounted on said segment for removal therefrom individually, and a type-bar and an operating key-lever mounted on each hanger, said segment being dismountable from said framework together with said hangers, type-bars and key-levers.
- 60 28. The combination with a framework, of a segment mounted thereon, hangers slidably mounted on said segment for removal therefrom individually type-bars mounted on the hangers, converging key-levers also mounted on the hangers, and sub-levers extending from the key-levers to the type-bars and also having bearings on the hangers; said segment being detachable from said framework together with the type-bars, key-levers and sub-levers.
- 65 29. The combination with a framework, of a segment mounted thereon and provided with guideways, hangers mounted on said segment by sliding on said guideways, type-bars mounted on the hangers, converging key-levers also mounted on the hangers, and sub-levers extending from the key-levers to the type-bars and also having bearings on the hangers; said segment being detachable from said framework together with the type-bars, key-levers and sub-levers; each hanger with its type-bar, key-lever and sub-lever forming a unit detachably mounted on the segment.
- 70 30. The combination with a framework, of a segment mounted thereon, a converging system of type-bars mounted on said segment, a converging system of key-levers also mounted on said segment and underlying the type-bars, connecting means between said key-levers and said type-bars, each type-bar arranged to swing substantially in the plane of its connected key-lever; each bracket arranged in a plane about parallel with the plane of the path of its associated type bar, said segment, with the attached type-bars and connected key-levers, being bodily dismountable from said framework, and a carriage-controlled universal bar mounted beneath said key-levers, to remain in the machine when the system of key-actions is removed.
- 75 31. The combination with a framework, of a segment mounted thereon, a system of type-bars mounted on said segment, a converging system of key-levers also mounted on said segment, connecting means between said key-levers and said type-bars; said segment, with the attached type-bars and connected key-levers, being bodily dismountable from said framework, and a comb to guide said key-levers, said comb also connected to said segment to be dismounted therewith.
- 80 32. The combination with a framework, of a segment mounted thereon, a system of type-bars mounted on said segment, a converging system of key-levers also mounted on said segment, connecting means between

- 7
- said key-levers and said type-bars; said segment, with the attached type-bars and connected key-levers, being bodily dismountable from said framework, and a frame connected 5 to said segment to be dismounted therewith, and including a guide-comb for the key-levers, a rest for the type-bars, and a stop for the key-levers.
33. The combination with a framework, 10 of a segment mounted thereon, a system of type-bars mounted on said segment, a converging system of key-levers also mounted on said segment, connecting means comprising sub-levers between said key-levers and 15 said type-bars; said segment, with the attached type-bars and connected key-levers, being bodily dismountable from said framework, and a frame connected to said segment to be dismounted therewith, and including a guide-comb for the key-levers, a 20 rest for the type-bars, and a stop for the key-levers; and returning springs extending from the key-levers to the sub-levers.
34. The combination with a framework, 25 of a segment mounted thereon, a system of type-bars mounted on said segment, a converging system of key-levers also mounted on said segment, connecting means between said key-levers and said type-bars; said segment, with the attached type-bars and connected key-levers, being bodily dismountable from said framework, a cross-bar whereon 30 said segment is mounted, said cross-bar being dismountably connected to said framework, and a guide-comb for said key-levers mounted upon said cross-bar.
35. In a typewriting machine having a keyboard and a framework, the combination with a space-key in front of the keyboard, 35 of means supporting said space-key to swing relatively to the keyboard for folding back over the keyboard for compactness when the machine is out of use, and means to enable said space-key when in normal position to perform its function.
36. The combination with a keyboard and a framework, of a bail pivoted on the framework and extending around the forward portion of the same and having a space-key, 40 whereby the latter may be swung back over the keyboard out of the way, a swinging frame mounted within the framework and operable by said bail when in normal position, and carriage-feeding means operable by said frame.
37. The combination with a keyboard and a framework, of a bail pivoted on the framework and extending around the forward portion of the same and having a space-key, 45 whereby the latter may be swung back over the keyboard out of the way, a swinging frame mounted within the framework and operable by said bail when in normal position, carriage-feeding means operable by
- said frame, a universal bar operable by the 50 key-board, and an arm operable by said universal bar to operate said carriage-feeding means, said arm operable by said swinging frame independently of said universal bar.
38. In a typewriting machine, the combination 55 with a hanger in the form of a plate, of a type-bar, a key lever, and a sub-lever, all pivoted on the same side of said plate, said sub-lever having a portion connected to the key lever and in the same plane therewith, the sub-lever being laterally offset at an intermediate point and connected to the type-bar on the same side thereof as said plate.
39. In a typewriting machine, the combination 60 with a hanger in the form of a plate, of a type-bar, a key lever, and a sub-lever, all pivoted on the same side of said plate, said sub-lever having a portion connected to the key lever and in the same plane therewith, the sub-lever being laterally offset at an intermediate point and connected to the type-bar on the same side thereof as said plate, said key lever and type-bar extending 65 forwardly from their pivots, and the sub-lever being located forward of said pivots.
40. The combination of a hanger in the form of a plate, a segment having guide-ways on which the hanger is slidable for mounting the hanger or removing it from 70 the segment, a key lever and a type-bar mounted on the hanger, operating means connecting the key lever to the type-bar, said lever normally extending in a direction transverse to that in which the hanger is 75 slidable, and means for locking the hanger on the segment.
41. The combination with a segment having guide-ways, of a series of hangers slidable in said guide-ways, for individually 80 mounting or removing the hangers, type-bars and key levers mounted on the hangers, and operating means connecting the key levers and type-bars, said key levers extending in a direction transverse to that in which 85 the connected hangers are slidable, whereby each hanger with the key lever and type-bar thereon may be removed or replaced as a unit without interfering with the other hangers.
42. The combination with a keyboard and 90 framework, of a bail mounted on the framework, and extending around the forward portion of the same and having a forwardly projecting space-key, said bail pivoted at its rear end to swing back over the stationary 95 key-board out of the way, and letter-feeding mechanism actuated by the space-key, said space-key when swung forward to operative position being automatically brought into operative relation to the letter-feeding mechanism.
43. In combination, a platen, a set of radial brackets in front thereof, a set of radial

- type-bars pivoted on said brackets and each extending forwardly from its pivot, a set of key-bearing converging levers pivoted on said brackets and extending forwardly therefrom, and a set of converging type-bar operating levers connected to said key-bearing levers and pivoted on said brackets, said operating levers and their pivots being located in front of the pivots of said type-bars and key levers and directly engaging the key levers and type-bars.
44. In combination, a set of type-bars, a set of plates forming brackets whereon the type-bars are mounted, a set of type-bar operating levers pivoted on said brackets to swing in a radial plane, and a set of key-bearing levers also pivoted on said brackets to work in the plane of said type-bars and connected to said operating levers, said operating levers and their pivots being located in front of the pivots of the type-bars and key levers, said brackets being detachably mounted, whereby any bracket, with the type-bar, operating-lever and key-lever, may be attached or detached as a unit.
45. The combination of a keyboard, a curving system of types of less width than the keyboard and in rear thereof, a system of rearwardly converging bars whereon said types are mounted, a system of key levers extending rearwardly from the keyboard and converging at their rear ends about coincidentally with the type-bars, said bars arranged to normally extend forwardly from their pivots to overlie their key levers, and to swing to a rearwardly extending position to print, connections from the rear portions of the levers to the type-bars, each key lever and its key arranged to move in substantially the vertical plane of its connected type-bar, and converging plates forming hangers whereon said key levers and type-bars are mounted, one plate for each key lever with its type-bar.
46. The combination of a platen, a system of type-bars, a system of key levers operatively connected to the type-bars, the bars and levers all arranged wholly in front of the platen and about on a level therewith, said type-bars mounted to strike on the upper side of the platen, but normally extending forwardly from their pivots, each type-bar overlying and in the same vertical plane with its key lever, a system of thin, converging plates, each forming an individual hanger common to both the key lever and its type-bar, and a segment upon which the plates are mounted, the type-bars placed so closely as barely to admit the plates between the type-bars.
47. The combination of a platen, a system of radial type-bars mounted to strike on top of the platen, a system of key levers, a system of converging sub-levers between the key-levers and the type-bars; all of said type-bars, key levers and sub-levers being mounted wholly in front of the platen, the key levers converging at their rear ends to lie in the same planes with their connected type-bars, and a system of thin, converging plates, each forming a hanger, each hanger having a type-bar, key lever and sub-lever thereon.
48. The combination with a system of type-bars, of a segment having radial slots on its front and rear sides, and hangers to which said type-bars are individually pivoted, said hangers in the form of plates forked to bestride the segment and fit in the slots thereof and each removable with its connected type-bar from the segment without interference with the mounting of the other hangers.
49. The combination with a system of type-bars, of a segment having radial slots on its front and rear sides, of hangers to which said type-bars are individually pivoted, said hangers in the form of plates forked to bestride the segment and fit in the slots thereof and each removable with its connected type-bar from the segment without interference with the mounting of the other hangers, and individual means to fasten each hanger detachably in position.
50. The combination with a set of type-bars mounted to swing in converging planes, of a set of duplicate converging plates, each plate forming a bracket or hanger for the type-bar, each plate parallel with its type-bar, a set of key levers converging to correspond with the convergence of the type-bars and hangers and mounted respectively upon said hangers, means connecting said key levers to said type-bars, and a separate converging sub-lever also mounted upon each of said hangers and each engaging its key lever and its type-bar, said levers at their key ends being bent out of their converging planes to bring the keys into straight transverse banks or rows.
51. The combination with a set of type-bars mounted to swing in converging planes, of a set of duplicate converging plates, each plate forming a bracket or hanger for the type-bar, each plate parallel with its type-bar, a set of key levers converging to correspond with the convergence of the type-bars and hangers and mounted respectively upon said hangers, means connecting said key levers to said type-bars, and a separate converging sub-lever also mounted upon each of said hangers and each engaging its key lever and its type-bar, each key lever and type-bar being mounted on the same side of the hanger plate, and the sub-lever being also mounted upon the same side of the hanger plate, but having between its ends a bend, whereby the type-bar end of the sub-lever

is brought into the plane of the hanger plate.

52. The combination with a set of type-bars mounted to swing in converging planes, of a set of duplicate converging plates, each plate forming a bracket or hanger for the type-bar, each plate parallel with its type-bar, a set of key levers converging to correspond with the convergence of the type-bars and hangers and mounted respectively upon said hangers, means connecting said key levers to said type-bars, and a separate converging sub-lever also mounted upon each of said hangers and each engaging its key lever and its type-bar, each key lever and type-bar being mounted on the same side of the hanger plate, and the sub-lever being also mounted upon the same side of the hanger plate, said key lever and sub-lever being in the same plane and connected by a knuckle-joint.

53. The combination with a set of closely-spaced type-bars, operable each independently of all the others and working in converging planes, of a set of hangers in the form of plates, each type-bar mounted face-wise to its hanger, and the hangers all in converging planes to correspond with the type-bars, converging, operating levers also mounted on said hangers to operate in the same planes as the type-bars, and keys for said levers.

54. The combination of a segment, converging hangers each in the form of a plate mounted upon said segment and rising therefrom, type-bars pivoted to said hangers above said segment and extending forwardly from said hangers, and convergent key-driven levers connected to said type-bars and overlying said segment and pivoted to said hangers.

55. The combination of a segment, converging hangers each in the form of a plate mounted upon said segment and rising therefrom, type-bars pivoted to said hangers above said segment and extending forwardly from said hangers, and convergent key-driven levers connected to said type-bars and overlying said segment and pivoted to said hangers, said key-levers extending in the planes of the type-bars and between the same and the segment.

56. The combination with a set of radiating type-bars, of a segment having opposite grooves on its outer and inner peripheries, radial plates forming hangers having forks bestriding the segment and inserted detachably in the grooves, said type-bars pivoted individually to said hangers, and individual means releasably securing the hangers.

57. The combination with a set of type-bars, of a segment, a set of hangers, each having at one end a pivoted connection to one of said type-bars and at the other end

means detachably connecting it to said segment, and a key-actuated lever also pivoted to each hanger and connected to the type-bar thereon, the hangers and levers being radially disposed.

58. The combination with a set of type-bars, of a segment, a set of hangers, each having at one end a pivoted connection to one of said type-bars and at the other end means detachably connecting it to said segment, and a key-actuated lever also pivoted to each hanger and connected to the type-bar thereon, the hangers and levers being radially disposed, the lever extending between the type-bar and the segment, and being in the same radial plane with the type-bar.

59. The combination with a set of type-bars, of a segment, a set of hangers, each having at one end a pivotal connection to one of said type-bars and at the other end means detachably connecting it to said segment, a key-actuated lever also pivoted to each hanger and connected to the type-bar thereon, the hangers and levers being radially disposed, the lever extending between the type-bar and the segment, and being in the same radial plane with the type-bar, and a radially-disposed sub-lever also pivoted to each hanger to connect the key lever with the type-bar thereon.

60. The combination with a revoluble platen and a keyboard in front thereof and about on a level therewith, of a cumbent segment between the platen and the keyboard, a set of hanger plates rising from said segment in front of the platen and detachably secured at their lower ends to said segment, type-bars pivoted upon the upper ends of said hangers, and so closely assembled that substantially the entire room between each type-bar and the next is occupied by the plate constituting the hanger for such type-bar, and connections from the keyboard to said type-bars.

61. The combination with a revoluble platen and a keyboard in front thereof and about on a level therewith, of a cumbent segment between the platen and the keyboard, a set of hanger plates rising from said segment in front of the platen and detachably secured at their lower ends to said segment, type-bars pivoted upon the upper ends of said hangers, and so closely assembled that substantially the entire room between each type-bar and the next is occupied by the plate constituting the hanger for such type-bar, and connections from the keyboard to said type-bars, said connections including converging levers mounted on said plates beneath the type-bars and working in the planes of the type-bars and operatively connected thereto.

62. The combination with a revoluble platen and a keyboard in front thereof and

about on a level therewith, of a cumbent segment between the platen and the keyboard, a set of hanger plates rising from said segment in front of the platen and detachably secured at their lower ends to said segment, type-bars pivoted upon the upper ends of said hangers, and so closely assembled that substantially the entire room between each type-bar and the next is occupied by the plate constituting the hanger for such type-bar, and connections from the keyboard to said type-bars, said connections including

converging levers mounted on said plates beneath the type-bars and working in the planes of the type-bars and operatively connected thereto, and also including converging sub-levers also mounted upon said hangers and connecting the first levers with said type-bars. 16

DISCLAIMER.

1,293,235.—*Burnham C. Stickney, Elizabeth, N. J.* TYPEWRITING MACHINE. Patent dated February 4, 1919. Disclaimer filed November 16, 1922, by the assignee, *Underwood Typewriter Company*.

Hereby enters this disclaimer—

“To that part of the claim in said specification which is numbered as claim 35 and which is in the following words, to wit:

“In a typewriting machine having a keyboard and a framework, the combination with a space-key in front of the Keyboard, of means supporting said space-key to swing relatively to the keyboard for folding back over the keyboard for compactness when the machine is out of use, and means to enable said space-key when in normal position to perform its function.”
